(57) **CLAIM**

The ornamental design for a packet with integral connector tab, as shown and described.

DESCRIPTION

FIG. 1 is a perspective view of packet with integral connector tab showing my new design;

FIG. 2 is a front elevation thereof;

FIG. 3 is a rear elevation thereof;

FIG. 4 is a left side elevation thereof;

FIG. 5 is a right side view thereof;

FIG. 6 is a top view thereof; and,

FIG. 7 is a bottom plan view thereof.

In the drawings, the dashed lines in FIGS. 1-7 are included to show environmental features and portions of the packet with integral connector tab that form no part of the claimed design.

1 Claim, 5 Drawing Sheets
